UNITED STATES PATENT OFFICE.

WILLIAM B. CROWELL, OF NEW YORK, N. Y.

DOOR-CHECKING DEVICE.

Original application filed May 10, 1923, Serial No. 638,072. Divided and this application filed December 17, 1925. Serial No. 75,974.

The present invention relates to an elevator door-operating mechanism, and more particularly to a device which is adapted for use in connection with the operation of elevator doors to attain cushioning or checking action. This application is a division of my application, Serial No. 638,072, filed May 10, 1923.

The primary object of the invention is to provide means for cushioning elevator doors and the like in both the opening and closing movements of the door, and which shall be adapted for operation to provide cushioning action when the door-operating levers are manually operated.

Another object of the invention is to provide cushioning or dampening means in which the action may be varied and regulated to attain any desired amount of cushioning or dampening effect.

With these and other objects in view, the invention comprises the various features hereinafter described and more particularly defined in the claims.

The invention may be best described in connection with the accompanying drawings, in which—

Figure 1 is a front view showing a pair of elevator doors to which toggle levers are connected for operating the doors, and showing my invention mounted in connection with the toggle levers;

Figure 2 is a vertical section of a device embodying the preferred form of the invention, showing the parts thereof in assembled or operative position;

Figure 3 is a plan sectional view taken on the line 3—3 of Figure 2; and

Figure 4 is a plan sectional view taken on the line 4—4 of Figure 2.

In Figure 1 of the drawing, the device, indicated by the numeral 1, is shown in operative relation to elevator doors 2 and 3 which are mounted in the usual manner to slide on overhead tracks. The mechanism usually employed for manually opening and closing elevator doors comprises a toggle lever of some form, to which a switch operating device is attached for cutting out the elevator operating current when the doors are open. The form of toggle lever indicated in the drawing comprises three members 4, 5 and 6. The member 6 is pivotally connected at 7 to the side of the elevator hatchway and is also pivotally connected at

8 to the member 5. The member 5 is pivoted at 9 to the elevator door 2 and is pivoted to the member 4 at 10, the member 4 being pivotally attached to the elevator door 3 at 11. A handle 12 is attached to the member 5, as indicated in the drawing, so that by pressing downward on the handle 12, the pivot 10 moves downward and the pivot 8 moves upward so as to draw the doors to the left in open position. By pressing the handle upward or by the mere act of removing downward restraint from the handle 12, the reverse action takes place, causing the closing of the doors.

The device which I have invented comprises means which may be attached to the levers of elevator doors or the like as in the manner indicated in Figure 1 of the drawings, whereby the elevator doors may be opened and closed without jar or noise. The form of my invention, which is shown in detail in Figure 2 of the drawings, comprises a cylinder casing 13 to which an upper cylinder head 14 and a lower head 15 are attached. Arranged to slide within the cylinder is a piston 16 which is attached to a piston rod 17, which passes through an opening 14' in the cylinder head 14 and is attached by a suitable means to the member 6 of the toggle lever. Attached to the piston is a leather cup 18 serving to attain smooth sliding action of the piston, and serving also to prevent leakage of pressure fluid between the piston and cylinder walls when the apparatus is employed as a power operated device for the operation of the toggle levers. Between the piston 16 and the upper cylinder head 14 is mounted a compression spring 19 by means of which the piston will be returned to its normal position after operation of the toggle levers to open the doors. The upper head 14 is attached to the cylinder casing 13 by means of screw threads 20, 21 so as to be adjustable in position thereon, by which the tension of the spring member 19 may be regulated.

Attached to the cylinder head 15 is a cup or a plunger cylinder 22 which is preferably made integral with the head, and which is adapted to hold a liquid such as oil or glycerine. Within the plunger cylinder is a plunger 23 which is attached to the piston rod 17. The plunger cylinder and plunger operating in the liquid therein in the manner

to be described constitutes a cushioning or dampening means for the apparatus, by which the movement of the piston 16 and parts attached thereto are controlled. In 5 the central portion of the plunger cylinder is an enlarged portion 22' in which the internal diameter of the plunger cylinder is increased in order to provide a clearance between the plunger and the cylinder walls when the 10 plunger reaches this part of the cylinder in its upward or downward movement. In order to control the movements of the plunger, I provide passages in the walls of the plunger cylinder for the flow of oil or 15 other liquid from one portion thereof to another. By regulating the flow of liquid by suitable means, the plunger and piston movements may be controlled. The oil passages referred to are indicated in the drawings by the numerals 24 and 25, the passage 20 24 leading from the upper portion of the plunger cylinder to the enlarged portion, and the passage 25 leading from the lower end of the plunger cylinder to the enlarged portion. Regulating screws 26 and 27 are 25 suitably positioned in the base or cylinder head 15 by means of which the openings through the passages may be varied so as to regulate the flow of liquid through the 30 passages during the operation of the device. Communicating between the enlarged portion of the plunger cylinder and the chamber at the lower end of the cylinder 13, is a passage 28 by means of which liquid which 35 may have escaped to the chamber between the cylinder 13 and the plunger cylinder 22, may be returned to the plunger cylinder. The plunger cylinder is closed at its top by 40 means of a cap 29 which provides bearings for the cylinder rod 17. The lower end of 45 the plunger cylinder is closed by means of a cap or a cylinder head 30 which is provided with a slot or other means for attaching the device to a support such as 31, indicated in Figure 1 of the drawings.

Any suitable liquid may be employed to attain the cushioning effect, such as oil or glycerine, but I preferably use a lubricating oil for the reason that this liquid will operate 50 for long periods without requiring attention.

The invention covered in the present application is adapted particularly for manual operation, that is, without other application 55 of power to the toggle levers than is attained by hand operation. If the toggle levers or elevator doors are to be operated by power, however, the apparatus may be employed with a connection for compressed air or other pressure fluid for operating the device, which may be supplied by means of a pipe 32 which is preferably connected so as 60 to pass through the lower cylinder head 15 and to extend upwardly through the chamber between the outer casing 13 and the

plunger cylinder walls 22 to a point above the level of liquid in the device. Without fluid pressure operation, however, the pipe 32 may be omitted entirely if desired, as will be apparent to those skilled in the art, in 70 which case the opening through the casing will be closed by any suitable closing means, or the pipe 32 may remain connected even though it is not used.

When it is desired to open the elevator 75 doors, the toggle levers are operated in the manner described above, thereby forcing the piston upwardly, compressing the spring 19 and moving the plunger 23 upwardly in its cylinder 22. The upward movement of the 80 plunger 23 thus produces traps some of the oil at the top of the cylinder 22. The oil which is trapped passes to the right through the port leading to the passageway 24, and passes downwardly therethrough past the 85 regulating screw 26 which controls the flow thereof to the enlarged section 22', thus checking the plunger at the top of the plunger cylinder, as desired. When the elevator doors are to be closed, the operator removes 90 the downward pressure of his hand from the handle 12, thereby permitting the spring 19 to actuate the piston 16. The spring 19 then forces the piston downwardly, together with the parts attached thereto, the plunger 23 95 passing the enlarged portion 22' of the plunger cylinder into the lower portion thereof where oil is trapped, and is forced through a port leading to the passage 25, in 100 which the oil passes upwardly and is controlled in its movement therein by the regulating screw 27, by means of which the cushioning effect, in the door-closing movement, is controlled. The liquid passing the regulating screw 27 returns to the interior of the 105 plunger cylinder above the plunger and will operate immediately to reduce cushioning action again when the elevator doors are to be opened. By adjusting the regulating screws 26 and 27, the movement of the liquid 110 through the passages 24 and 25 may be controlled and the cushioning effect in the opening and closing movements of the door may therefore be independently regulated.

It is to be understood that various changes or modifications may be made in the device described without departing from the spirit or scope of the invention as defined in the claims.

What is claimed as new is—

1. In a door check and closer, door closing means, a checking device of unitary structure comprising a cylinder, a plunger therein, means for operatively connecting one of said parts to said door closing means, and means for attaining restricted flow of a liquid from one side of the plunger to the other to attain a substantially uniform retarded movement of the door near the end portions of both its opening and closing movements. 120
125
130

2. In a device of the class described, a cylinder adapted to hold a liquid, an enlarged portion in said cylinder intermediate its ends, a plunger in said cylinder adapted for sliding movement therein, and means for causing a gradual escape of the liquid from the path of said plunger as it approaches either end of the cylinder, comprising passage-ways from either end of the cylinder to the said enlarged portion, and means for limiting the area of said passage-ways to effect a cushioning of the last portion of the movement of said plunger toward either extreme position. 70
3. In a door check and closer, a checking mechanism of unitary structure comprising a cylindrical casing, a plunger therein adapted to move from one end of the cylinder to the other, means for by-passing a liquid from end portions of the cylinder to an intermediate portion thereof so as to retard substantially uniformly the movements of the door in portions of its opening and closing movements corresponding to the relative movements of the said plunger in the said cylinder with respect to the said means for by-passing liquid, and means for regulating the passage of liquid through said by-pass means to control the cushioning movement of the said door. 75
4. In a device of the class described, a cylinder adapted for holding a liquid, said cylinder having a portion intermediate its ends in which the internal diameter thereof is increased, a plunger in said cylinder constructed to fit in both end portions of the cylinder and arranged to be disengaged from both said end portions and to be located in said intermediate portions at one point in its movement in the cylinder, passageways in the walls of the cylinder for transferring liquid from one portion of the cylinder to another during movement of the plunger therein, and means for independently regulating the flow of liquid in the said passageways to produce a gradual escape of the liquid from the path of said plunger as it approaches either extreme position. 80
5. In a device of the class described, a checking or cushioning means comprising a plunger and a plunger cylinder, operating connections between one of said parts and a mechanism to be operated thereby, a spring adapted to move the plunger in one direction, a cylinder casing in which the spring is located connected with the plunger cylinder so as to form a unitary structure having a space between the cylinder casing and the plunger cylinder in open communication with said plunger cylinder so as to permit passage into and return of liquid from the cylinder casing to said plunger cylinder during the movement of the plunger in the plunger cylinder, and means for by-passing liquid from the end portions of the plunger cylinder to an intermediate portion thereof 85
- so as to control the movements of said plunger in the end portions of the cylinder, and thereby to cushion the movements of the operated mechanism at the ends of the forward and return strokes. 90
6. In a door check and closer, a checking device comprising a cylinder adapted for holding a liquid, the said cylinder having a portion intermediate its ends in which the internal diameter thereof is increased, a plunger in said cylinder constructed to fit the end portions of said cylinder and having a clearance when positioned in the intermediate enlarged portion, said plunger being arranged to be disengaged from both said end portions and located in said intermediate portion at one point in its movement in said cylinder, passageways communicating between the ends of the cylinder and said enlarged portion, and means in said passageways for regulating the passage of liquid therethrough whereby the movement of the plunger in the cylinder toward the ends thereof, corresponding to the initial opening and final closing movements of the door, is controlled. 95
7. In a device of the class described, a cylinder, upper and lower adjustable heads on the cylinder, a piston in the cylinder, a compression spring above said piston, means for regulating the tension of the spring, a piston rod attached to said piston, a second cylinder attached to the lower head of the first cylinder and adapted to hold a liquid therein, said second cylinder having an enlarged portion intermediate its ends, a plunger in the second cylinder attached to said piston rod, passageways communicating between the ends of the said second cylinder and the enlarged portion therein, and means for regulating the passage of liquid through the said passageways during movement of the plunger in said second cylinder to retard substantially uniformly the movements of the plunger. 100
8. In a door check and closer, the combination of a cylinder, a rod passing axially thru the cylinder, a second cylinder of smaller diameter mounted with its upper end within the first-named cylinder so that a space is left between the second cylinder and the wall of the first cylinder to form a reservoir, a plunger mounted on said rod within the second cylinder and means associated with the second cylinder for checking the movement of the plunger in both directions to retard correspondingly the movement of the door. 105
9. In a door check and closer, the combination of a cylinder, the lower end of which is arranged to form an oil reservoir, a rod passing axially thru the cylinder, a door, a connection between the rod and the door, means for moving the rod and door, a double acting dashpot attached to the lower end of said cylinder and having oil passages connecting 110
- 120
- 125
- 130

the same with the cylinder, and means connecting the door with the dashpot to control the movements of the door.

10. In a door check and closer, an upright cylinder, the lower end of which forms an oil reservoir, a rod passing axially thru the cylinder, a door, a connection between the door and rod for transferring the motion of one to the other, a double acting dashpot

15 attached to the end of said cylinder and comprising a second cylinder of smaller diameter co-axially mounted on the lower end of the first cylinder, a plunger mounted on said rod and engaging in the second cylinder, an oil passage connecting the first cylinder with the second cylinder, and means for retarding the movement of the plunger to retard correspondingly the movement of the door.

20 11. In a door check and closer for controlling the movements of a door, in combination, a member in which energy is stored during the opening movement of the door to serve as the closing force, a checking mechanism comprising a cylinder and plunger

25

therein, means for connecting said plunger to the door, and means for attaining restricted flow of a liquid out of the path of the advancing plunger as it nears the end portion of both its door opening and door closing strokes, said means comprising passages in the wall of said cylinder thru which the liquid may flow at a rate dependent upon the size of said passages.

12. In a door check and closer for controlling the movements of a door, in combination, a member in which energy is stored during the opening movement of the door to serve as the closing force, a checking mechanism comprising a cylinder and plunger 40 therein, means for operatively connecting one of said parts to the door and means for attaining restricted flow of a liquid out of the path of the plunger and from one side of said plunger to the other as the door 45 nears the end portion of both its opening and closing movements.

Signed at Hoboken, New Jersey this 15th day of December, 1925.

WILLIAM B. CROWELL.
